Application July 5, 1932, Serial No. 620,884

5 Claims. (Cl. 20—16)

This invention relates to closures and operating devices therefor, and has for an object the provision of a closure and an operating and supporting device therefor of novel and highly efficient design, which is particularly well adapted for though not necessarily limited to use in conjunction with closures for relatively large openings, such as the doorway of a garage, market, or the like.

10 A more detailed object is to provide a novel type of mechanism for so supporting a closure that it can be moved optionally to open or closed position by swinging it about an axis extending longitudinally of the closure, the entire weight of 15 the closure being carried at all times solely by the supporting mechanism.

15 A more detailed object is to provide a closure supporting and operating device of the general character indicated whereby the closure may be held releasably in either open or closed position and which is also adapted to move the closure to open position by raising it bodily to an overhead position so as to leave the entire doorway unobstructed for passage therethrough and/or observation of or access to articles which are enclosed by the closure when in closed position.

20 It is a further object of the present invention to so arrange the supporting and operating device that when the closure is in open position, it 25 is disposed horizontally and extends through the uppermost portion of the doorway with a portion of the closure extending outwards therefrom so as to dispense with the necessity of an awning to protect goods displayed inside the doorway 30 from the direct rays of the sun.

25 Another object of our invention is to provide an efficient operating mechanism for the closure whereby it may be moved easily to open and to closed positions, from a convenient location which 35 may be remote from the closure when desired.

30 A further object is to provide the operating mechanism with a suitable lock whereby manipulation of the operating mechanism by anyone other than authorized persons is prevented.

35 A still further object is to provide a novel device for counterbalancing the weight of the closure whereby the movement of the closure in either direction is greatly facilitated and which is 40 adapted to hold the closure stationary in any position between its two extremes of movement without its having to be fastened.

45 A further object of the present invention is to provide means for supporting the closure throughout its entire range of movement and at least one point intermediate the ends thereof, thereby

making it possible to employ a closure which would otherwise be of excessive length, inasmuch as it would be subjected to too severe bending stresses on account of the distance between its points of support.

5 A further object in this connection is to provide a novel design of closure having reinforcing means for preventing the closure from flexing either by sagging at those portions of the closure which are between the points of support thereof, 10 or by twisting as a result of the application of torsional stresses thereto as in opening or closing the door.

Another object is to provide a closure and supporting and operating means therefor, having 15 the characteristics above set forth, which is of simple and rugged design, capable of highly efficient and facile operation, and in the design of which particular attention has been paid to positiveness of operation in respect to moving the 20 closure to either its open or its closed position and also in respect to the retention of the closure in selected position.

25 The invention possesses other objects and valuable features, some of which, with the foregoing, will be set forth in the following description of the preferred form of our invention. It is to be understood that we do not limit ourselves to the specific disclosure made by the said description, as we may adopt variations of the preferred form 30 within the scope of our invention, as set forth in the claims.

Referring to the drawings:

35 Figure 1 is a perspective view illustrating a building provided with a closure incorporating the principles of the present invention.

40 Figure 2 is a transverse, vertical sectional view which may be considered to have been taken upon the line 2—2 of Figure 1 with the direction of view as indicated by the arrows.

45 Figure 3 is a detail view in horizontal section taken upon the line 3—3 of Figure 2, with the direction of view as indicated by the arrows.

50 Figure 4 is a transverse vertical sectional view similar to Figure 2, but showing a slightly modified form of counterbalancing mechanism. In this figure the closure is shown in its closed position.

55 Figure 5 is a view similar to Figure 4, but showing the closure in its open position.

Figure 6 is a horizontal sectional view, the plane of section being taken upon the line 6—6 of Figure 4 with the direction of view as indicated. Portions of the figure are broken away to reduce its size.

Figure 7 is a view in elevation showing the inside face of the closure itself and showing the novel type of reinforcing used in the construction thereof.

6 Figure 8 is a detail view in transverse vertical section taken substantially upon the line 8—8 of Figure 7 with the direction of view as indicated.

10 Figure 9 is a detail view in transverse vertical section, the plane of section being taken adjacent to the center supporting bracket for the closure. This plane may be assumed to have been taken upon the line 9—9 of Figure 7 with the direction of view as indicated but with the closure swung 15 to horizontal position.

15 In terms of broad inclusion, the device of the present invention comprises means for supporting a closure such as a garage or store door of relatively large proportions, optionally in closed 20 relationship to an opening or doorway, or in open position wherein the closure is elevated and lies in a plane substantially perpendicular to its closed position and closely adjacent the periphery of the opening, thereby leaving substantially 25 the entire opening unobstructed. The closure itself is provided with reinforcing means resisting the flexing stresses to which it may be subjected, and the supporting means for the closure are of such design that as many additional supports 30 may be provided intermediate the ends thereof as may be desired or necessary to meet the requirements of any particular installation, which feature also goes to the sufficiency of the invention in making it possible successfully and practically to employ doors and other closures of 35 relatively great length. Means are provided for moving the closure to and from closed position; and a novel design of counterbalancing mechanism is provided, whereby movement of the closure in either direction is greatly facilitated. 40 This counterbalancing mechanism also is of novel design and is adapted to retain the closure in any position, i. e. at either of its two extremes of movement or in any intermediate position, 45 without its having to be fastened. The operating device is of the self-locking type; that is to say, after the closure has been moved to either fully opened or closed position by means of the operating device, the closure cannot be removed 50 from this position by any means other than the operating device itself. Moreover, the operating device may be provided with a suitable lock, making it impossible for access to be had to the enclosed space controlled by the closure, by anyone 55 other than authorized persons.

60 Specifically describing one of the preferred embodiments of our invention, it is illustrated upon Figure 1 as having been adapted to a store or market building indicated in its entirety at 65 11, having an opening or doorway 12 in the front wall 13 thereof. It will be observed that the doorway 12 is of relatively large proportions, inasmuch as it occupies substantially the entire area of the front wall 13 of the building 11. Our invention makes it possible to employ a door 14 for this large doorway 12, which is a rigid member adapted to be moved bodily and without altering the shape of the door itself, when opening or closing the door.

70 Although we do not wish to be so limited, we prefer to employ a plurality of units or panels 16, which may be assembled into planer alignment and rigidly fastened in such arrangement so as to provide the door 14 of the necessary width. The construction of the door is best illustrated

upon Figure 7, which shows all the panels 16 rigidly secured as by rivets 17 to a longitudinally extending truss 18. This truss 18 comprises longitudinal members 19 and 21, which preferably are angle irons and which constitute the members 5 to which the panels 16 are secured by the rivets 17. The longitudinal members 19 and 21 are interconnected by transverse members 22 which extend vertically when the door is in vertical position, and transverse members 23, which extend diagonally between the longitudinal members 19 and 21. The arrangement of members 19, 21, 22 and 23, which is illustrated upon Figure 7 is merely exemplary, it being understood that the particular design of truss 18 to be employed 15 depends upon the dimensions of the door 14 in any particular installation. In any event, however, the longitudinal member 19 which is uppermost when the door is disposed in a vertical plane constitutes the compression member of the 20 truss 18, whereas the lowermost longitudinal member 21 will be in tension. Thus it may be seen that the truss 18, whatever its specific design, supports those portions of the door 14 which are disposed between the points of support of the 25 door, from sagging, even though those points of support are relatively remote from each other.

As will be explained herein below, the door 14 lies in a horizontal plane when open, and accordingly we have provided means for supporting 30 those portions of the door which are intermediate the points of support thereof when the door is in open or horizontal position also. This is accomplished by designing the truss 18 as a two-way truss, for which purpose rods 26 are associated 35 with the longitudinal members 19 and 21. Each of these rods 26 extends between the transverse vertical members 22 which are adjacent the supporting brackets 27, it being understood, therefore, that the transverse members 22 to which the 40 ends of the rods 26 are secured are disclosed at or closely adjacent to the points of support of the door 14. Where the ends of the rods 26 are anchored to these transverse members 22 they are disposed closely adjacent the plane of the 45 inner face of the panels 16; but from these points of anchorage of the rods 26 they incline outwards from that plane, as clearly shown upon Figure 8 to the central portions 28 thereof, which are retained spaced from the panels 16 by saddles 29. 50 Thus it may be seen that each of the rods 26 cooperates with the particular portion of the longitudinal member 19 or 21, as the case might be, with which it is associated, the rod 26 operating as the tension member of the truss and the associated portion of the longitudinal member 19 or 55 21, as the case might be, operating as the compression member. In other words, the rods 26 serve as the tension members of the truss and the longitudinal members 19 and 21 serve as the 60 compression members of the truss when the door 14 is in horizontal or open position, whereas the longitudinal member 19 serves as the compression member and the longitudinal member 21 serves as the tension member when the door 14 65 is in vertical or closed position.

Means are provided for mounting the door for pivotal movement about an axis which extends longitudinally of the door. The position for this axis is so chosen that whereas the door occupies a 70 vertical plane between the jambs 31 at opposite ends of the doorway 12, when closed, the door opens by swinging upwards to its open position wherein it lies in a horizontal plane closely adjacent the upper peripheral edge, i. e. the lintel 75

32, of the doorway 12. The advantage of this arrangement is that when the door is open, it is substantially completely withdrawn from the doorway 12, leaving the entire area of the opening through which persons can pass unobstructed, and exposing to unobstructed view articles displayed inside the doorway 12. We accomplish this by disposing the axis about which the door swings, in parallelism with the plane of the door 10 and lying within a plane which inclines at substantially forty-five degrees with respect to the plane of the door and from the neutral axis of the door, i. e. from the horizontal line within the door which includes the center of gravity of the door. This horizontal line, i. e. the neutral axis, is indicated at 33, and from this line 33 a plurality of arms 34 rigid with the inner face of the door, incline, the direction of inclination being toward that edge 36 of the door which is uppermost when the door is closed, and the angle of their inclination with respect to the door being substantially 45°. These alined arms 34 are provided with means for bracing them to hold their outer ends perfectly rigid with respect to the door 14, the preferred bracing means being a horizontal arm 37 extending from the outer end of each inclined arm 34 and perpendicularly to the inner face of the door, where it is rigidly secured preferably by being riveted or otherwise permanently attached to one of the transverse members 22, it being preferred also that the associated inclined arm 34 is also rigidly attached to the same transverse member 22. Thus it may be seen that each inclined arm 34 co-operates with the associated arm 37 and the associated transverse member 22 of the truss 18 to define a bracket on the inner face of the door 14. One of these brackets will be provided adjacent each end of the door; and as many additional brackets intermediate the ends thereof will be provided as are found to be necessary as determined by the particular details of installation, these details including such factors as the weight of the door, its overall length, and the like.

45 Brackets 38 thus defined are provided with alined hubs 39, which may be merely blocks 41 of metal secured to the brackets 38 and having holes 42 therethrough for the reception of a shaft or other suitable pivot means. As pointed out hereinabove, the common axis of all these holes 42 lies in the plane which inclines at 45° with respect to the plane at the door and which includes the neutral axis 33 of the door.

55 Supporting means are provided to which the alined hubs 39 are pivotally connected, these supporting means being in the form of stationary brackets 46 rigid with any suitable portion of the building 11. For example, the stationary brackets 46 associated with the door bracket 38 which are proximal the ends of the door may be mounted rigidly upon the jams 13, although they would operate equally efficiently if they were secured to any other supporting structure within or forming a portion of the building 11. For each of the intermediate door brackets 38 a stationary bracket 47 is mounted upon any suitable supporting structure, but inasmuch as it is desired usually to leave the doorway 12 unobstructed when the door is open, we prefer that these intermediate stationary brackets 47 extend downwards from above. To fulfill these requirements it or they, as the case might be, should be rigidly secured upon any suitable overhead structure such as the roof 48, as illustrated upon Figure 9. When so arranged, a slot 49 is formed in registry with

each of the intermediate stationary brackets 47, this slot 49 extending downwards within the door from the upper edge 36 thereof, so as to permit the upper edge 36 of the door to pass the vertical member 51 of the associated intermediate stationary bracket 47, as clearly shown upon Figure 7. For the sake of convenience throughout the remainder of the specification, both the end brackets 46 and the intermediate brackets 47 will be indicated by the reference numeral 27, these stationary brackets being the supporting members for the door 14.

5 Whereas the axis about which the door turns when opening or closing lies within a plane which inclines at 45° with respect to the plane of the door and from the center of gravity of the door, the distance of the pivotal axis from the door measured in a line perpendicular to the door may be varied without departing from the spirit of the present invention. We prefer, however, that the distance of this axis from the door be such that it lies within a plane perpendicular to the plane of the door and approximately one-half the distance from the neutral axis 33 to the upper edge 36. This will cause the door 14 to assume a position as it swings upwards into a horizontal plane, wherein it extends through the doorway 12 and closely adjacent the lintel 32. Moreover, approximately the lower one-third of the door will extend outside the door, whereas the upper two-thirds will be disposed within the building 11, as clearly shown upon Figure 9. Hence, when in open position, the lower third of the door which extends outwards beyond the plane of the front wall 13 of the building 11 serves as an awning, inasmuch as it will protect from the direct rays of the sun articles which are displayed within the building 11 and closely adjacent the doorway 12. Furthermore, this particular arrangement of parts, wherein the axis about which the door rotates is disposed substantially as hereinabove described, will cause the door to lie in a horizontal plane when opened fully, which is closely adjacent to the lintel 32, thereby disposing the door in an overhead position, leaving substantially the entire opening of the doorway 12 unobstructed.

50 Means are provided for counterbalancing the door so that it will remain in any position to which it may be moved without having any fastening 50 means incorporated therewith.

55 Figure 2 shows one modification of counterbalancing device wherein a weight 56 is pivotally secured to and suspends from an arm 57 which is an extension of the inclined arm 34 of one of the door brackets 37. The axis 33 of the pivot 58 whereby the weight 56 is connected to the arm 57 lies in the same inclined plane which includes the axes of the hubs 41 and the center of gravity of the door. Accordingly, the center of gravity 60 of the door and the axis of the pivotal connection 58 of the weight 56 to the arm 57 are disposed upon diametrically opposite sides of the axis about which the door turns, and inasmuch as the counterweight 56 is of sufficient mass effectually to counterbalance the door 14, it will be seen that the turning moment of the counterweight 56 if only one be employed, or of the counterweights, if there be several, will at all times be equal to the turning moment of the door 70 in the opposite direction. This follows from the fact that as the lever arm by which the weight 56 applies its force in one direction, increases in length, so also does the lever arm by which the door applies its force, but in the opposite 75

direction of rotation, increase. Accordingly, even without being fastened, the door 14 will remain in any position to which it is moved, regardless of whether that position be either fully opened or fully closed, or in any position between these two extremes of movement.

Figures 4, 5 and 6 show a modified form of counterbalancing mechanism wherein the counterbalancing effect is identical with that of the mechanism just described, but wherein an added convenience is afforded. Here, instead of being pivoted directly to an extension of the inclined arm of the door bracket, the counterweight 61 is pivotally suspended from a lever 62, adjacent the forward end thereof, and the after end of the lever 62 is pivoted to an idler link 63, which in turn is pivoted to a stationary member such as an extension 64 of the associated stationary bracket 66. An arm 67, which is an extension 20 of the inclined member 68 of the associated door bracket 69 is pivoted as by a pin 71 to the lever 62 intermediate the ends thereof, so that the weight imposed by the counterweight 61 upon the lever 62 is thus applied in a downward direction 25 to the after end of the arm 67, which is upon the opposite side of the axis about which the door turns, from the center of gravity of the door. The link 63 provides a moving fulcrum for the lever 62, permitting the entire lever 62 to move 30 away from the front wall 13 of the building, while the door swings from fully open position or from fully closed position to a position intermediate these two extremes of movement. This shifting of the lever 62 compensates for the arcuate movement of the weight 61, the result being that the weight 61 moves in a more nearly vertical line and thereby requiring the provision of materially less space for its accommodation. Moreover, this arrangement of parts disposes the counterweight 40 61 for movement in a line which lies between the axis about which the door turns and the front wall 13, whereas in the first described modification the weight 56 is at all times upon the opposite side of the axis of rotation from the front wall 13.

As may readily be understood, one or more of the counterbalancing mechanisms and of either modification thereof may be employed, the number and type of counterbalancing devices depending upon the circumstances of any particular installation. It is believed, however, that most installations will operate most efficiently if one of the counterbalancing devices be associated with each end of the door.

Means are provided for operating the door, i. e., for moving it from open to closed position, or from closed to open position. This operating means is of such a nature that the door may efficiently be operated from a location remote from the doorway, if desired. Preferably, however, the parts are so arranged that the door may be opened and closed from outside the building 11. For this purpose a rod 76 is journaled in and extends through one of the jambs 13 in perpendicularity with the plane of the front wall 13. The outer end of the rod 76 carries a manually operable crank 77 whereby the rod may be turned by persons standing outside the building 11. To the inner end of the rod 76, which preferably is supported by means of a bracket 78 rigid with the associated stationary bracket 27, a crank 79 is rigidly secured and to the outer end of this crank 79 a link 81 is pivotally connected as by a crank pin 82. The other 75 end of the link 81 is pivotally connected to the

proximal door bracket 38 at a point between the axis about which the door turns and the door itself. Accordingly, when the rod 76 is turned from the position indicated upon the Figure 2 the crank 79 will be swung upwards, pushing the link 81 upwards and thereby causing the door 14 also to be swung upwards about the axis of the hubs 39. The parts are so proportioned and arranged that movement of the door 14 from fully opened to fully closed position requires rotation of the crank 79 and rod 76 through substantially 180°. However, after arrival of the door 14 at either fully opened or fully closed position, the rod 76 and crank 79 can be rotated through a few more degrees, thereby causing the crank 79 to pass the dead center position before engaging the stop means which are provided to prevent further movement thereof. This prevents movement of the door 14 from either its fully opened or fully closed position without first turning the rod 76, preferably by means of the handle 77, and thus prevents inadvertent dropping of the door from its overhead position, to the possible injury of persons standing therebeneath. Moreover, by providing the rod 76 or 25 the handle 77 with any suitable type of lock 80, adequate means are provided for preventing opening of the door 14 by any one other than properly authorized persons. Whereas any suitable stop means may be provided, we have found 30 it convenient to so arrange the parts that the crank 79 or the link 81 comes into engagement with one of the members of the associated stationary bracket 27 after having moved a few degrees past its top dead center position, and with 35 a lug 84 carried by the link 81 after having moved a few degrees past the bottom dead center position. Or, if desired, the lug 84 may be carried by the crank itself and come into engagement with the link 81 after the crank has passed 40 its bottom dead center position.

Whereas it has been stated hereinabove that the counterweight 56 or 61 as the case might be is connected to the associated door bracket 38 through the expedient of an arm 57 or 67 45 respectively, which arm is an extension of the inclined member of the associated door bracket, it is not necessary that this extension be perfectly straight, the only requirement being that the axis of the pivotal connection of the weight to 50 that arm lie in the plane which also includes the axis about which the door turns and the center of gravity of the door. Preferably the arm 57 is disposed upon the opposite side of the journal 86, which is carried by the associated 55 stationary bracket, from the door bracket 38 to which it is connected by means of a pin 87, extending rotatably through the journal 86, both the arm 57 and the bracket 38 being rigidly connected to the pin 87. Accordingly, the turning 60 moments of the counterweight and of the door respectively will be applied to the journal 86 from opposite sides thereof, thus preventing the development of any torque tending to twist the associated stationary bracket 27, such as that 65 which would be developed if both the arm 57 and the bracket 38 were disposed at one end of the journal. The same effect is gained by connecting the link 81 to the arm 57, but upon the opposite side of the pivot pin 87 from the counterweight 56, so that rotational effort applied to the door from the crank 79 also will be upon the opposite end of the journal 86 from the bracket 38. Preferably the arm 57 and the bracket 38, in addition to being rigidly secured 70 75

to the pin 87 are rigidly interconnected by means of a strip 88, one end of which is rigid with the arm 57 and the other end of which is rigid with the bracket 88 with the intermediate portion 89 of the strip 88, extending through the associated stationary bracket 27, as clearly shown upon Figure 3. This bracket consists of upper and lower arms 91 and 92 respectively, each of which is provided with a block 93 of suitable cushioning material such as rubber, in position to be engaged by the intermediate portion 89 of the strip 88, just prior to the time at which the door arrives at fully opened or fully closed position. Hence, these cushioning blocks 93 provide the stop means for the door, holding the door against moving beyond its extreme positions and without permitting the door to come into engagement with any structure on the lintel 32, jambs 13, or the sill 94.

Inasmuch as the force applied to the door in moving it toward or away from open position is applied adjacent only one end of the door, it may be desirable under certain circumstances of installation to substitute a continuous shaft 96 (see Figure 6) for the several pins 87 whereby the door brackets 88 are pivotally connected to the associated stationary brackets 27. This shaft 96 is keyed or otherwise rigidly connected to all of the door brackets 27 and to all of the arms 57 or 67, as the case might be, to which the counterweights 56 or 61 respectively are connected, and is journaled in all of the stationary brackets 27, the result being that when rotational effort is applied at but one point of the shaft 96, this rotational effort is applied to the door at several points by the several door brackets 88. Accordingly this detail of construction co-operates with the truss 18 in distributing stresses imposed upon the door throughout the entire door. Toward this same end the truss 18 is provided with means for preventing racking of the door from a perfectly flat plane. This is conveniently accomplished by means of gusset plates 101 provided wherever transverse members 22 and/or 23 of the truss 18 are connected to the longitudinal members 19 or 21. These gusset plates assist the transverse members 22 and 23 in acting as cantilever beams when a force is applied to the door which would tend to make one end of one of these transverse members 22 or 23 as the case might be, to move away from the plane of the door without there being applied a force of equal magnitude and in the same direction at the other end of that same transverse member.

Accordingly, this detail of construction of the door and the means for distributing rotational effort to several points within the door when the door is being opened or closed, co-operate with the provision of the intermediate stationary brackets 47 by permitting the use of a door which otherwise would be excessively long, due to its not being reinforced against sagging, bending and torsional stresses.

Whereas any suitable type of weight may be employed for the counterweight 56 or 61, as the case might be, it should be pointed out that the preferred form consists of a hollow container, as best illustrated upon Figures 4 and 6, which may be shipped empty, and into which any suitable material, such as sand, water, bricks, or the like may be placed after installation. This per-

mits of accurate adjustment of the counterweights, so that they are capable of exerting just the desired amount of turning movement against the pins 92 or the shaft 96, as the case might be, to counterbalance the door 14.

It should further be pointed out that whereas the fully opened position of the door 14 has been described throughout the specification and claims as being in a substantially horizontal plane, this and similar terms are intended to be construed broadly enough to include closure construction wherein the door in its open position is at sufficient inclination from the horizontal to insure adequate drainage therefrom.

We claim:

1. A frame for a movable panel comprising a plurality of members affixed to said panel, said members comprising spaced longitudinal members and transverse members interconnecting said longitudinal members at spaced intervals to define a truss, one of said longitudinal members being in compression and another in tension when said panel is in one position and both of said longitudinal members being in compression when said panel is in another position, and additional longitudinal members cooperating with said first mentioned longitudinal members to define a second truss the plane of which is disposed angularly with respect to the plane of said first mentioned truss, said additional longitudinal members being in tension when said panel is in said other position.

2. In a panel frame of the character described, a truss comprising spaced chords and web members interconnecting said chords, and means reinforcing said chords against flexure out of the plane of said truss, said reinforcing means comprising another truss the plane of which is disposed angularly with respect to that of said first mentioned truss.

3. In a panel frame of the character described, a truss comprising spaced chords and web members interconnecting said chords, and means reinforcing said chords against flexure out of the plane of said truss, said reinforcing means comprising means cooperating with each of said chords to define another truss the plane of which is disposed angularly with respect to that of said first mentioned truss.

4. In a panel frame of the character described, a truss comprising spaced chords and web members interconnecting said chords, and means reinforcing said chords against flexure out of the plane of said truss, said reinforcing means comprising another chord rigid with and spaced from each of said first mentioned chords and lying outside the plane of said truss.

5. In a movable panel frame of the character described, a truss comprising spaced chords and web members interconnecting said chords, said chords being subjected to stresses of opposite type in one position of said panel, and an additional chord associated with each of said first mentioned chords, all of said first mentioned chords being subjected to the same type of stress and all of said additional chords being subjected to the opposite type of stress in another position of said panel.

WESLEY W. EAGER.
COLUMBUS A. TIERNEY. 70
